(57) CLAIM

The ornamental design for a bottle, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front perspective view of a first embodiment of a bottle, embodying our new design;

FIG. 2 is a back perspective view thereof;

FIG. 3 is a front view thereof;

FIG. 4 is a back view thereof;

FIG. 5 is a first side thereof;

FIG. 6 is a second side view thereof;

FIG. 7 is a top view thereof; and

FIG. 8 is a bottom view thereof;

FIG. 9 is a front perspective view a second embodiment of a bottle, embodying our new design;

FIG. 10 is a back perspective view thereof;

FIG. 11 is a front view thereof;

FIG. 12 is a back view thereof;

FIG. 13 is a first side view thereof;

FIG. 14 is a second side view thereof;

FIG. 15 is a top view thereof; and

FIG. 16 is a bottom view thereof;

FIG. 17 is a front perspective view of a third embodiment of a bottle, embodying our new design;

FIG. 18 is a back perspective thereof;

FIG. 19 is a front view thereof;

FIG. 20 is a back view thereof;

FIG. 21 is a first side thereof;

FIG. 22 is a second side view thereof;

FIG. 23 is a top view thereof; and

FIG. 24 is a bottom view thereof;

FIG. 25 is a front perspective view of a fourth embodiment of a bottle, embodying our new design;

FIG. 26 is a back perspective view thereof;

FIG. 27 is a front view thereof;

FIG. 28 is a back view thereof;

FIG. 29 is a first side view thereof;

FIG. 30 is a second side view thereof;

FIG. 31 is a top view thereof; and,

FIG. 32 is a bottom view thereof.

The broken lines shown in the drawings depict portions of the bottle that form no part of the claimed design.
